RAILWAY CAR TRUCK

Charles D. Barrett and Charles R. Whitehead,
Altoona, Pa.

Application December 8, 1944, Serial No. 567,166

2 Claims. (Cl. 105—197)

1

This invention relates to railway car trucks of a type in which the bolster is yieldingly supported by helical springs with capacity for limited lateral motion. The operation of such trucks at high speeds is invariably attended by the building up of lateral oscillations of the bolsters and consequent excessive swaying of the car bodies.

The chief aim of our invention is to obviate the above drawbacks, which desideratum is realized in practice as hereinafter more fully set forth, through provision of a simple and reliable means whereby the lateral movements of the bolsters are effectively damped in such a manner as to preclude excessive oscillation and thus improve the riding qualities of the trucks.

A further aim of our invention is to attain the aforementioned advantages in a restraining means which can be readily applied to existent car trucks without requiring any alteration whatever in them and without interfering with their normal mode of operation.

In the drawings,

Fig. 1 is a cross sectional view of a railway car truck conveniently embodying the present improvements.

Fig. 2 is a horizontal section taken as indicated by the angled arrows II—II in Fig. 1 with the mid-portion of the truck bolster broken out to expose the restraining means; and

Fig. 3 is a fragmentary detail view in section taken as indicated by the angled arrows III—III in Fig. 1.

The truck partially delineated in these illustrations for the purpose of exemplifying our invention is generally of the construction disclosed in U. S. Patent #2,287,963, granted to us on June 30, 1942, wherein the bolster 5 is hollow with its ends extending into the guide windows 6 and 7 of the side frames 8 and 9 and therein supported by groups of vertical axis helical springs 10 and 11, said springs resting on the spring plank 12 which connects said side frames. Additional cushioning is afforded by pairs of semi-elliptic springs 15 and 16 located within the hollow of the bolster 5. As shown, the center straps 17 and 18 of the springs 15 and 16 have spherical contact at their tops with the upper web of the bolster 5, while their inner ends slidably engage rounded supports 19 and 20 within the bolster hollow. The outer ends of the springs 15 and 16, on the other hand, are engaged in recessed cap pieces 21 and 22 at the tops of rockers 23 and 24 respectively disposed in the midst of the helical spring groups 10 and 11 and having their lower

2

ends fulcrumed on the spring plank 12. Adjacent its ends and at opposite sides thereof, the bolster 5 is provided with pairs of spaced lugs 13 and 14, which, by cooperation with the side frames 8 and 9, limit lateral motion incident to sidewise flexure of the springs 10 and 11.

The vibration restraining means with which the present invention is more particularly concerned includes a leaf spring 25 which is longitudinally arranged in the interval between the bolster 5 and the spring plank 12. From Fig. 1 it will be noted that the spring 25 bears directly against the bottom web of the bolster at the center and that its ends are upwardly rounded as at 26, 27 and engaged within crosswise-disposed hold-down strap elements 28, 29 upstanding from the spring plank 12 with interposition of renewable wear plates 30 and 31 upon which they frictionally bear. The hold-down elements 28 and 29 may be in the form of U bolts with their extremities passing down through the wear plates 30 and 31 respectively and being suitably anchored in apertures in the spring plank 12. Thus through frictional action of the spring 25 with the spring plank 12 and the bolster 5, swaying of the latter is effectively controlled and excessive vibration thereof prevented, the elements 28 and 29 serving as retaining devices to hold said spring in place. If desired or required, a multiple leaf spring may be substituted for the spring 25 depending on the styles or carrying capacities of the trucks with which the vibration restraining means is to be used. In trucks where our restraining spring is employed, we preferably space the lugs 13 and 14 (Fig. 2) somewhat further apart than ordinarily in order to correspondingly increase the permissible lateral motion of the bolster.

Having thus described our invention, we claim:

1. In a railway car truck having a pair of side frames rigidly connected by a transverse member, a resiliently-supported bolster with its ends extending through vertical guideways in said frames, and a leaf spring with its mid portion bearing upward against the bottom of the bolster, and its ends slidably bearing downward against the top of the aforesaid transverse connecting member; wear-taking and hold down means for the spring ends including wear plates interposed between them and the connecting member and fixed to the latter and strap elements extending crosswise over them and secured to said connecting member.

2. The invention according to claim 1, in which the ends of the leaf spring are upwardly

curved, and in which the strap elements are in the form of U bolts with their ends passing down through the respective wear plates, and anchored in the transverse connecting member.

CHARLES D. BARRETT.
